UNITED STATES PATENT OFFICE.

JOHN BLACKLOCK, OF TORONTO, ONTARIO, CANADA, ASSIGNOR TO THE UNIVERSAL KNITTING MACHINE COMPANY, OF SAME PLACE.

CIRCULAR-KNITTING MACHINE.

SPECIFICATION forming part of Letters Patent No. 236,698, dated January 18, 1881.

Application filed September 9, 1878. Patented in Canada August 29, 1878, for five years; extended December 6, 1880, for ten years.

To all whom it may concern:

Be it known that I, JOHN BLACKLOCK, of the city of Toronto, in the county of York, in the Province of Ontario, Canada, manufacturer, have invented certain new and useful Improvements in Circular-Knitting Machines, (patented to me in Canada August 29, 1878, No. 9,129;) and I do hereby declare that the following is a full, clear, and exact description of the same.

My invention relates to improvements upon cylindrical knitting-machines; and it consists in the construction and arrangement of parts, as hereinafter more fully set forth, and then pointed out in the claims.

In the accompanying drawings, Figure 1 is a cross-section, and Fig. 2 a plan, of a machine embodying my improvements. Figs. 3, 4, and 5 are details.

20 A is the frame of machine, provided with the usual clamping-bracket A' for setting up.

B is the vertical needle-cylinder, and C the combined cam-cylinder and cog-ring, operated by a crank and toothed wheel, as usual.

25 D is the yarn-feeder, attached directly to the combined cam-cylinder and cog-ring, directly over the cam, by which arrangement the feed is always in position to work instantly backward or forward.

30 E is the vertical knitting-cylinder cam, the line of whose inflection is elevated in the center at e, and is depressed on each side of the center at e' e'. The ends of the cam are formed by adjustable wing-pieces F F. These wings are pivoted at one end, and are connected, by stud-pins e², with the ends of the pivoted levers G, which levers are, in turn, connected to a nut, h, on the adjusting-screw H, in such manner that the position of the wings, as a part of the cam, may be varied, as desired, by turning the screw up or down. The object of this arrangement is to enable the operator to lengthen or shorten the stitch at pleasure, or, in other words, to increase or decrease the tension of the stitch, so as to produce tightly or loosely knitted work. The wings at each end permit the machine to be worked backward or forward with equal facility.

45 I is a bracket-arm, attached to the cam-cylinder by a socket and set-screw connection. The upper end of this bracket terminates at a

point immediately above the center of the vertical knitting-cylinder, and has attached to it, by the screwed pin I', the cone-shaped ribbing dial or cylinder J. The axes of the ribbing and vertical cylinders correspond, and the diameter of the ribbing-cylinder, at the lower edge, corresponds with the circle of the inner side of vertical needles, sufficient space being left, of course, for the work to pass through. The ribbing-needle cylinder is held stationary by lugs j, engaging with the lug b on the cylinder B.

K is the cam-cylinder of the ribbing attachment. This cam-cylinder is securely attached to the pin I', and with it turns as the bracket 65 I revolves. The cam-cylinder K overlies the ribbing-cylinder, and is provided with a cam, L L', by the contact of the needles, with which they are given an outward and downward motion on the one stroke and an upward and inward motion on the return stroke. The position of the cams on the ribbing attachment and on the vertical cylinder correspond, so that the needles in working intersect. The parts of the ribbing attachment are so proportioned that 70 the needles which operate in the vertical cylinder are used in the ribbing-cylinder—that is, they are transferable from one cylinder to the other. The needles may thus be changed from plain work to ribbing work, and inversely 75 without dropping the stitches.

M is a fender attached to the yarn-feeder. The object of this fender is to keep open the latches of the ribbing-needles while they are taking their yarn; and to this end the fender 85 is provided with a knife-edge, and so placed that it engages with the latches of the needles and holds them open for the required length of time. It will be seen that this fender is double-pointed and that it is curved in cross-section, as seen in Fig. 1, by which means it 90 operates on both sets of needles, and the machine can be run in either direction with equal facility.

The ribbing-cam is provided with a switch, 95 N, by means of which the ribbing-needles can be thrown in and out of action. To throw the ribbing-needles out of action the switch N is depressed by the lever N'. This movement permits the needles to pass behind the cam, 100 which revolves without imparting any motion to them. The object of this arrangement is to

enable the operator to produce what is called a "welt" at the top of a stocking or other ribbed work. So soon as sufficient welt is formed the ribbing-needles are thrown into action 5 again.

I claim as my invention—

1. The combination, with the vertical knitting-cylinder B, cam-cylinder C, arm I, cone-shaped ribbing-dial J, and overlying cam-cylinder K, of the double-pointed fender M, curved in cross-section, substantially as described, and for the purpose specified.

2. The vertical knitting-cylinder cam E, having its line of inflection elevated in the center 10 at e and depressed at each side of the center at e', combined with the adjustable and pivoted wing-pieces F, stud-pins e², pivoted levers G, and adjusting-screw H, substantially as set 15

forth, whereby, by the changing of the position of the wing-pieces F, the operator may 20 increase or decrease the tension of the stitch for the production of tightly or loosely knitted work, as specified.

3. The vertical knitting-cylinder cam E, having its line of inflection elevated in the center 25 at e and depressed at each side of the center at e', the adjustable and pivoted wing-pieces F, stud-pins e², pivoted levers G, and adjusting-screw H, in combination with the double-pointed knife-edged fender M, curved in cross- 30 section, whereby the machine may be run in either direction with equal facility, as specified.

JOHN BLACKLOCK.
